(57) **CLAIM**

The ornamental design for a barbecue light, as shown and described.

DESCRIPTION

FIG. 1 is a front perspective view of a barbecue light;

FIG. 2 is a front elevational view thereof;

FIG. 3 is a rear elevational view thereof;

FIG. 4 is a left side elevational view, of which the right side elevational view is a mirror image;

FIG. 5 is a top plan view; and,

FIG. 6 is a bottom view.

The portions shown in broken lines are environmental and form no part of the claimed design.
